FLASH BOILER

Charles S. Turner, Detroit, Mich.

Application August 29, 1935, Serial No. 38,436

12 Claims. (Cl. 122—33)

This invention relates to the controlled heating of fluids, and is of particular utility where the rate of heat transference to and the temperature of the heated fluid are desired to be held within close limits, not only in their average values and final result upon the fluid discharged at the outlet, but throughout all portions of the apparatus.

An important object is the provision of such apparatus enabling the quick yet closely regulatable transference of large quantities of heat to fluids having low specific heats, which fluids may also be of relatively volatile character, such as hydrocarbon oils, without danger of localized burning.

15 A further object is the provision of a fluid-regulated still or retort incorporating temperature regulating means having a large excess cooling capacity, and so arranged that the metal of which the entire assembly is formed may be cooled very quickly, whereby special heat-resisting metals such as certain chrome-steels may be employed which must be very quickly cooled from an elevated temperature in order to anneal them and prevent their acquiring a dangerous degree of

25 brittleness. In the construction of stills for the cracking of oil it has been found impractical to employ such heat-resisting steels because of the fact that the walls cannot be chilled rapidly enough when the still is shut down to prevent 30 tempering the walls to undesired hardness in the objectionable manner referred to, and an important object of the present invention accordingly resides in the provision of an improved still or retort of the character indicated which can

35 be fabricated of such special steels, and accordingly may be operated at higher rates and temperatures, which further not only incorporates a novel and improved form of temperature-regulating means affording a previously unattainable 40 degree and accuracy of control, and absolute safety against localized burning, but enables chilling the heat-exposed walls of the assembly so quickly, when desired, as to enable annealing the metal even though it be of that type which requires almost instantaneous quenching to soften.

Another object is the provision in conjunction with fluid-regulated heating means of a novel and improved method of transferring heat from one portion to another of the apparatus to equalize heat absorption and reduce the ratio of maximum temperature to rate of heat absorption, by circulating and utilizing the regulating fluid in a novel manner.

55 Another object is the provision of improved heating means of the character indicated in

which the precise control of temperature and heat transference remarked upon may be achieved despite variances of output demand upon the heating apparatus, differences of temperature of the fluid as it is initially supplied, and/or differences in the temperature of the regulating or cooling medium.

5 Another important object is the provision of an improved boiler wherein a fluid level may be maintained at any desired point, and effectively 10 regulated with relation to and in order to maintain any desired temperature, despite wide differences in the output of and rate of flow through the apparatus, and wherein such fluid level may be carried at a relatively high point if desired, to 15 enable heat absorption by the fluid throughout a large proportion of the active surface of the apparatus, yet in which the level may be so quickly controlled in response to variances of demand and output that the danger of flooding portions 20 of the apparatus located beyond the heating apparatus and intended to be kept dry, is effectively precluded.

An object incident to that last set forth is the provision of apparatus capable of successfully 25 functioning as a true flash boiler, incorporating generating water tubes in which a reduced water level may be positively and accurately maintained at a point below their full evaporative capacity, without danger of complete flooding of the tubes 30 or the discharge of water into the receiver or receiving apparatus, and wherein such level may be maintained despite wide variations of the rate of flow through and the demand upon the boiler.

Efforts to perfect a true flash boiler whose output 35 is capable of wide variation have met with failure from a practical standpoint heretofore because no method of controlling the water level therein has been known which is not so sluggish as to be dangerous, since control of the water level must be quick and sensitive enough in its response to provide effective safeguard against flooding or discharging water to the receiver. The overcoming of the difficulties mentioned may be said to constitute in brief a summary of the objects 40 of this invention, which is intended to so interconnect the saturated steam generating and superheating means as to make the superheating effect dependent upon the water level in the saturated steam generating portions, and control the 45 water level in the latter in response to the output temperature of superheated steam, and further aims to so accurately control the water level in this manner that no reservoir whatever need be located in the furnace, and that output variations 50

55

as wide as those encountered in the operation of the boilers of steam driven vehicles may be accommodated.

Other objects and advantages will be apparent from the following description wherein reference is made to the accompanying drawings illustrating preferred embodiments of the invention and wherein similar reference numerals designate similar parts throughout the several views.

10 In the drawings:

Figures 1 and 2 are somewhat diagrammatic vertical and horizontal sectional elevational views respectively of an oil cracking still incorporating the principles of this invention;

15 Figure 3 is a detailed section taken substantially on the line 3—3 of Figure 1 and looking in the direction of the arrows;

20 Figure 4 is a detailed cross section taken substantially on the line 4—4 of Figure 3 and looking in the direction of the arrows;

25 Figure 5 is a diagrammatic elevational view of a flash boiler construction incorporating the present invention;

Figure 6 is a section taken substantially on the line 6—6 of Figure 5 and looking in the direction of the arrows; and

25 Figure 7 is a view analogous to Figure 6, on a smaller scale, of a modification.

Referring now to the drawings, reference character 30 10 designates the front or furnace chamber of a still or retort whose walls define a double pass furnace, the front portion being indicated as heated by an oil burner diagrammatically shown as of the jet type, the nozzle being represented at 12 and the burner controllable as by 35 means of fuel valve 13. The gases after traveling upward through the front section and through the cross-over 14, pass downwardly through the back section 15, whence they discharge through 40 the stack 16. The back section incorporates a preheater in the form of simple tiers of sinuously wound pipes 18, arranged in series. To these the fluid desired to be heated—in the illustrative instance crude oil—is initially fed through the 45 supply pipe 20.

At its upper end the preheater discharges into connecting pipe 22, which delivers the oil therefrom to the fluid-water regulated front section connected in series therewith and also constituting in effect a single pipe throughout its entire length. The walls of the component pipe of which the front section is formed, however, as shown best in Figure 4, are constituted by a smaller pipe 24 coiled in the form of a tight helix 50 and having its convolutions welded together as at 26 to form and seal a conduit therewithin. The conduit, which is generally designated 25, serves to conduct the oil delivered to its lower end by pipe 22 through the front furnace section in 55 which the major portion of the heating is effected, and may discharge the heated oil at the top, as through delivery pipe 26. The assembly comprising the conduit 25 defined by the helically coiled pipe 24 is arranged to line the entire 60 wall of the furnace 18 and directly absorb heat from the burner. In the construction illustrated the conduit 25 is for this purpose shown as closely coiled about the interior, thus forming the entire heat absorbing wall of the furnace.

70 The longer helical passage provided by the coiled pipe 24 constitutes a heat regulating jacket, and the temperature of the fluid (oil) passing directly through the central conduit 25 may be governed by the regulated introduction of a controlling or regulating fluid into the encircling

75 conduit 24. The regulating fluid may comprise water, which is fed from supply pipes 28 coiled similarly to or one lying outside each turn of the main conduit 25, and connected as by means of feeders 30 to the pipe 24 at spaced intervals therealong. In a petroleum still intervals of about three linear feet along main conduit 25 have been found satisfactory. The flow through each feeder 30 may be regulated by a control valve 32, and thermo-couples as 35, or other temperature indicating means, may be provided at similar intervals in order to enable the operator by regulating such valves to hold the temperature of the oil or other fluid at desired levels throughout the entire length of the apparatus. A main valve 42 is also provided in the water supply main 43. The regulating fluid circulates rapidly in the tube 24. If water is used it of course at once boils in such a still and circulates in the form of steam. In so repeatedly traveling from the 20 front, heat-exposed face of the assembly to the back, the regulating fluid picks up heat at the front and delivers it to the cooler rear walls and the oil at the back, after which it travels to the front, picks up more heat, and again carries it to the back, thus equalizing the delivery of heat to the oil over the entire surface of the assembly 25 reducing the temperature of the hotter faces of the tubes in proportion to the amount of delivered heat and final temperature, reducing the 30 danger of localized burning and enabling operating the still at higher average rates of heat transference than has been safely possible heretofore.

35 Thus when a fluid, such as oil, having a relatively low specific heat is to be heated, localized burning may nevertheless be effectively prevented by complete control allowing maintenance of every portion of the heating apparatus at safe temperatures, despite which a maximum temperature and rate of heat delivery may be maintained considerably higher than was heretofore feasible. Since relatively constant flow conditions ordinarily prevail in such stills, only minor changes in the settings of valves 32 are required during operation under the usual conditions. Due to the safeguarding effect of the steam jacket provided by conduit 24, and its regulating influence, much higher average rates of heat transference to the oil may be employed than in conventional arrangements incorporating no such safeguard, as stated above. The rates and temperatures may in fact be such that the use of one of the special steels mentioned becomes desirable. With my improved arrangement there is no danger of embrittlement of such steels when it becomes necessary to shut down the still, if the following procedure is followed: The burner is first lowered and the oil shut off and cleared from the still 50 passages 25. The burner is set at such level as will enable to metal to be held at the wanted temperature for annealing (ordinarily about 1650° F. for such steels). Main water valve 42 is closed to cut off the water supply at this time, and the individual control valves 32 are opened fully. The metal is allowed to "soak" at the elevated temperature as long as is required for the annealing operation—ordinarily merely long enough for it to reach uniform temperature. The burner is then shut down and the valve 42 opened to deliver the full flow of water to jacket tubing 24, the quick cooling effect corresponding in its rapidity to quenching. Any steam generated during this as well as all generated during regular operation discharges through steam pipe 44 connected to 55

the end of tube 24, and such steam may of course be used or disposed of as desired.

Figures 5 and 6 show an adaptation of a similarly coiled pipe 24' to the construction of combined superheating and regulating means for a flash boiler having saturated steam generating portions whose walls are similarly defined by the coiled tube 24'. The passage 25' within the same and which constitutes the saturated steam generating passage, is sealed by the welded seam 26' extending along the helical line of juncture between the turns of pipe 24'.

A plurality of such units may of course be arranged in parallel or in any other desired disposition between headers, as 54-48, constituting respectively water feeding and saturated steam off-take headers, to which connections are made from each unit by pipe sections 55-56 welded in the ends of the helical conduit assemblies as at 57. All headers and connecting pipes may lie outside the furnace or heating chamber, shown defined by walls 61. The water supply may be delivered to header 54 from water pipe 52, which incorporates a thermostatically regulatable throttle valve 53. From the receiver 48 saturated steam may be conducted through pipe 65 to the lower end of the coiled conduit 24', through which it rises and in which it is superheated. It is to be observed, however, that a great proportion of the superheating will occur above the water level, indicated at 70, and a much smaller proportion below it, the amount of superheat, and accordingly the temperature of the discharged superheated steam, thus depends upon the water level. It will also be apparent that by virtue of this coordination the temperature of the superheated steam discharged by such an assembly is an index of the water level, which may thus be regulated (by the throttle valve 53) to maintain the level at any desired point. Such regulation is, as indicated, preferably accomplished automatically by means of the thermostatic valve-operating means 75, mounted directly in the output steam header and quickly responsive to changes of the temperature of the superheated steam, and connected to throttle valve 53 in such manner that in response to a use of output superheated steam temperature it increases the opening of the throttle valve to allow the level to rise and reduce the superheating surface, while a fall of superheated steam temperature, such as is caused by undue reduction of the effective superheating surface, (rise of water level) results in reducing the valve opening to allow the water level to fall, by virtue of the reduced ratio of water supply to rate of vaporization. This compensates by raising the superheat temperature. Thus a balance is struck and maintained which so long as the burner or heat source is operating at constant temperature positively maintains a predetermined level. The functioning of this apparatus is moreover automatically responsive to changes in the amount of heat supplied by the burner or other heat source. The effect of turning down the burner will, by reducing the heat delivery and the temperature of the superheated steam, result in reducing the throttle valve opening, lowering the water level so that the rate of steam generation is reduced, but the temperature of the output steam is maintained, by reason of the resultant increase of superheating surface. Continued reduction of applied heat, as by turning down the burner to the point of shutting it off, results in also shutting off the water supply at the throttle valve, but a level of

water always remains in the portion of the tube assembly within the zone of heating.

As shown in Figure 7, it is not essential that the coiled superheating tube envelope the entire saturated steam generating passage, and such portion may extend down the tube assembly only far enough to cover the area within which the water level is maintained, while yet providing the desired superheating surface. The coiled superheating conduit is in this embodiment designated 24'. The saturated steam generating tube is partly formed by the simple pipe 56', which connects the lower end of each such assembly to the water header 54', or other water supply source, shown as similarly controllable in response to 53'. The parts may be so proportioned that the water level always remains within the area encircled by the tube-portion 24', and the other portions and principles of operation of the modified construction will be seen to be so analogous to those of the embodiment of Figures 5-6 as to need no re-description. Like portions have been given like reference characters, with the addition of the distinguishing exponent "2" to each.

While it will be apparent that the illustrated embodiments of the invention herein disclosed are well calculated to adequately fulfill the objects and advantages primarily stated, it is to be understood that the invention is susceptible to variation, modification and change within the spirit and scope of the subjoined claims.

What I claim is:

1. A flash boiler comprising in combination with a heating chamber having walls, water supply and steam offtake means located outside said walls, saturated steam generating means comprising a tubular channel extending through said chamber, a throttle valve in said water supply means whereby a reduced water level may be held in said saturated steam generating channel within said heating chamber, saturated steam collecting means connected to an upper end of said channel, superheating means connected to the outlet of said saturated steam collecting means and comprising a conduit coiled in the form of a tight helix about at least the portion of said channel within which said water level is held, and thermostatic operating means for said throttle valve responsive to the temperature of steam superheated in said superheating means and arranged to reduce the inflow of water to the saturated steam generating channel in response to a fall of temperature of the superheated steam, and to increase such inflow in response to a rise in temperature of the superheated steam, and to maintain the water level, despite such variation, in the upper portion of the saturated steam generating channel when the source of heat is functioning normally.

2. A flash boiler comprising in combination with a heating chamber and a source of heat therewithin, water supply and steam offtake means located outside the chamber, a water drum connected to said supply and also located outside said chamber, tubular saturated steam generating channel portions connected to said drum and extending through said chamber, superheating means connected to the outlets of said generating channel portions and helically coiled about at least a portion of said channel portions and in intimate heat conductive relation therewith, means for throttling the supply of water to said channel portions to maintain a water level within a portion thereof encircled by said superheating means, thermostatic controlling means for

said throttling means responsive to the temperature of the steam emanating from said superheating means and arranged to reduce the inflow of water to the saturated steam generating channels upon a fall of temperature of the superheated steam temperature.

3. A flash boiler comprising in combination with a heating chamber and a source of heat there-within, water supply and steam offtake means located outside the chamber, tubular saturated steam generating means connected to said water supply means, exposed to the heat of said heating chamber and having walls composed at least partly of a coiled element defining a separate passage way coiled about said generating means, said coiled element constituting a superheater and having metallic walls integral with those of the generating means, throttling means for holding a water level in said saturated steam generating means, means for conducting steam from the saturated steam generating means to said coiled superheater element, and means for regulating the throttle means and so the water level in the saturated steam generating means in response to the temperature of the superheated steam.

4. A flash boiler comprising in combination with a heating chamber and a source of heat, water supply and steam offtake means located outside the chamber, tubular saturated steam generating means connected to said water supply means, exposed to the heat of said heating chamber and having walls composed at least partly of a tube defining a separate superheater passage, said tube being coiled in the form of a helix and metallically integral with the walls of said saturated steam generating means, throttling means for holding a water level in said tubular generating means, means connecting the generating means and the superheater tube, whereby saturated steam from the former may flow through and be superheated in the latter, and means for regulating the throttling means and so the water level in the generating means in response to the temperature of the superheated steam.

5. A flash boiler as set forth in claim 4 in which at least a portion of the walls of the tubular saturated steam generating means are formed entirely by said superheater tube said tube coiled in the form of a tight helix having its convolutions welded together along the steam between them.

6. A flash boiler as set forth in claim 4 in which at least a portion of the walls of the tubular saturated steam generating means are formed entirely by said superheater tube, said tube having its convolutions welded together along the seam between them.

7. A flash boiler comprising integrated metallic portions defining a water receptacle in the form of a relatively short passage inclined from the horizontal, for generating saturated steam, a relatively much longer superheater passage coiled about the exterior of the receptacle and in heat exchange relation with the interior thereof, means for feeding water to said receptacle, throttling means for said water feeding means, and means

for controlling said throttling means in response to the temperature of the steam superheated in the superheater passage.

8. A flash boiler comprising integrated metallic portions defining a water receptacle in the form of a relatively short passage inclined from the horizontal, for generating saturated steam, a relatively much longer superheater passage tightly coiled about the exterior of the receptacle and in heat exchange relation with the interior thereof, means for feeding water to said receptacle, throttling means for said water feeding means, and means for controlling said throttling means in response to the temperature of the steam superheated in the superheater passage.

9. A flash boiler comprising integrated metallic portions defining a water receptacle in the form of a relatively short passage inclined from the horizontal, for generating saturated steam, a relatively much longer superheater passage coiled about the exterior of the receptacle and in heat exchange relation with the interior thereof, means for feeding water to said receptacle, throttling means for said water feeding means, and means responsive to the temperature of the superheated steam for controlling said throttling means.

10. Means for heating fluids, comprising in combination with a source of heat, a substantially helically coiled tubular jacketing element, continuous means sealing the space between the convolutions thereof to provide an independent central direct passage therethrough, said element being exposed to direct radiation from said source of heat only upon one side, whereby a regulating fluid flow through said tubular element passes alternately and repeatedly from the exposed side to the rear and vice versa, and may equalize the delivery of heat to all portions of another fluid within the central passage by surrendering heat to the portion thereof within the same but nearer the rear.

11. A flash boiler usable in conjunction with a source of heat and comprising a water receptacle portion for generating saturated steam and a relatively long superheater passage connected in series and integrated with said water receptacle portion for ready heat interchange therewith, said superheater passage comprising a relatively long tube coiled about and forming the external wall of the receptacle portion, means for feeding water to said receptacle portion, and throttling means for said water feeding means regulable in response to changing characteristics of the steam emanating from the superheater passage to maintain a variable water level in said portion of the receptacle which is integrated with said superheater passage, whereby changes of such water level may control the superheating action of said passage.

12. A flash boiler as set forth in claim 11 in which the tube forming said superheater passage extends integrally from the exterior to the interior of said receptacle portion to provide direct metallic heat paths therethrough.

CHARLES S. TURNER. 65
